UNITED STATES PATENT OFFICE.

ROLAND C. CONINE, OF BATH, NEW YORK.

EMBALMING INSTRUMENT.

1,112,982.

Specification of Letters Patent.

Patented Oct. 6, 1914.

Application filed June 30, 1914. Serial No. 848,227.

To all whom it may concern:

Be it known that I, ROLAND C. CONINE, a citizen of the United States, residing at Bath, in the county of Steuben and State 5 of New York, have invented certain new and useful Improvements in Embalming Instruments, of which the following is a specification.

My invention relates to embalming instruments and has for its object to provide a tube used for the purpose of draining the arteries and veins of the human body prior to the operation of embalming.

Another object is to provide an instrument of this character including a slidable frame adapted to break clots formed in the blood whereby the latter may freely flow from the body.

With these and other objects in view, the 20 invention consists in the novel construction, arrangement and combination of parts as will be hereinafter specifically described, claimed and illustrated in the accompanying drawings, in which,

25 Figure 1 represents a longitudinal sectional view of the device, Fig. 2 represents a transverse sectional view on the line 2—2 of Fig. 1, and, Fig. 3 represents an enlarged detail view of the open end of the tube and the clot breaker or agitator.

30 Referring to the drawing in detail, wherein similar reference numerals designate corresponding parts throughout the several views, the numeral 5 indicates the casing of 35 elongated cylindrical formation having open ends and screw threads at one end adapted to coöperate with the cap or closure 6 having an aperture therethrough. A branch pipe 7 extending at an oblique angle to the 40 tube 5 communicates with the latter adjacent its closed end and is adapted to be connected with a detachable flexible tube 8 for pumping and conducting the fluid from the body to a suitable receptacle.

45 A rod 9 is positioned within the tube 5 and projects a distance outwardly through the aperture in the cap 6 and is provided with a suitable handle 10 exteriorly of the latter. The rod 9 is adapted for sliding 50 movement through the cap 6 and is provided at its end opposite the latter with a frame 11 consisting of a plurality of bowed or curved spring members connected at their ends and retained in curved position by securing devices 12 secured to the rod 9. A piston or

collar 13 is secured on the rod 9 adjacent the frame 11 and is slidably mounted in the tube 5.

In use, the vein or artery is punctured and the open end of the tube 5 inserted 60 therein. The frame 11 is moved longitudinally through the casing 5 until it occupies the space between the branch conducting pipe 7 and the cap 6 whereby the fluid is permitted to flow freely through the tube 65 5, branch tube of pipe 7, flexible tube 8 and into the receptacle (not shown). When the tube 5 becomes clogged by a blood clot or other solid body lodging therein, the frame 11 is moved downwardly through the casing 70 5 and simultaneously rotated by the operator, thus effectively breaking the clot or solid body into parts which are drawn outwardly with the flow of blood.

What I claim is:

75 1. A device of the character described comprising a tube, a branch pipe communicating with said tube adjacent one end of the latter, a rod slidable through said tube, a piston on said rod movable within said tube, a handle on said rod exteriorly of said tube, and a frame on the opposite end of said rod slidable and rotatable in said tube.

80 2. A device of the character described comprising a tube, a branch pipe communicating with said tube adjacent one end of the latter, a rod positioned within said tube, a handle on one end of said rod exteriorly of said tube, a piston secured on said rod and movable longitudinally through said 90 tube, and a plurality of spring members secured to the opposite end of said rod slidable and rotatable in said tube.

95 3. A device of the character described comprising a tube, a branch pipe communicating with said tube adjacent one end of the latter, a rod positioned in said tube, a handle on one end of said rod exteriorly of said tube, a piston on said rod movable longitudinally through said tube, and a plurality of 100 spring members secured in bowed position on the opposite end of said rod slidable and rotatable in said tube.

In testimony whereof I affix my signature in presence of two witnesses.

ROLAND C. CONINE.
